UNITED STATES PATENT OFFICE.

LEVIN H. CLOGG, OF PHILADELPHIA, PENNSYLVANIA.

DESIGN FOR A TIP-CUP FOR UMBRELLAS.

SPECIFICATION forming part of Design No. 20,275, dated November 11, 1890.

Application filed June 27, 1890. Serial No. 357,005. Term of patent 3½ years.

To all whom it may concern:

Be it known that I, LEVIN H. CLOGG, a citizen of the United States, residing in the city of Philadelphia, State of Pennsylvania, have 5 invented a new and original Design for Umbrella and Parasol Tip-Cups, of which the following is a specification, reference being had to the drawing annexed to and forming part of this specification.

10 My invented design is clearly shown in the accompanying drawing; and it consists, essentially, of a vertical cylindroid having the exterior lines of the vertical sections through the central line of the cylindroid in the form

of a cyma curve, said cylindroid having the 15 surface of the convex portions roughened and broken in appearance and surfaces of the concave portions smooth and plain.

I claim—

The design for a tip-cup, substantially as 20 shown and described.

In witness whereof I have hereto set my hand, in the presence of two subscribing witnesses, this 25th day of June, 1890.

LEVIN H. CLOGG.
